COOLING DEVICE

Gordon Joseph Pardon, Abbotsford, British Columbia, Canada

Application January 30, 1939, Serial No. 253,667

4 Claims. (Cl. 257—74)

This invention relates to a device for rapidly cooling milk or any other liquid by means of agitation and a cooling fluid.

An object of the present invention is the provision of a cooling device which requires a relatively small amount of power for operation.

Another object is the provision of a cooling device of extremely simple construction and yet which effectively and rapidly cools liquids.

10 A further object is the provision of a cooling device adapted to keep oil or grease from the working parts thereof and dirt away from the liquid being cooled.

There are numerous devices for cooling milk 15 by utilizing water as the cooling means and motive power. The majority of these, however, are extremely complicated in construction and require considerable water pressure for operation. As this type of device is usually used on farms 20 where there is not a great deal of pressure in the water systems, not many of the known coolers are practical. The relatively great expense of some makes it impossible for the average farmer to buy them. There are cooling devices of simple 25 construction but unfortunately they are so simple that they will not operate properly and, therefore, will not cool the milk as rapidly as is necessary. In others, there is nothing to prevent dirt or the oil and grease used to lubricate them from 30 getting into the milk.

This invention overcomes the above-mentioned disadvantages by providing a cooling device of extremely simple construction having a novel means of suspending the working parts thereof 35 whereby friction is reduced to a minimum so that a fluid under relatively low pressure may be utilized as the cooling means and motive power. This device is constructed in such a manner that dirt, oil or other foreign matter cannot get into 40 the liquid being cooled.

The present invention consists essentially of a cooling device comprising a cover adapted to rest upon the top of a receptacle, a housing supported 45 above the cover, an agitator extending freely through the cover and below the latter, a bearing suspended from the housing adapted to carry the agitator, and fluid operated means in the housing for causing the agitator to rotate, as 50 more fully described in the following specification and illustrated in the accompanying drawing, in which—

Figure 1 is a side elevation partly in section of the cooling device mounted upon a receptacle 55 which is also partly in section,

Figure 2 is a plan view of the device with part of the top broken away.

Figure 3 is a fragmentary sectional view taken on the line 3—3 of Figure 1, and

Figure 4 is a reduced side elevation of a receptacle, part of which is broken away, showing the cooling device in operative position.

Referring more particularly to the drawing, A is the cooling device adapted to be seated on a receptacle or can B. As the device is particularly designed for cooling milk, it is made to fit a receptacle B having continuous, vertical sides, as shown, or it may be made to fit the well known type of milk can, the diameter of the top of which is less than that of the bottom thereof.

The cooling device A consists of a cover 10 in the form of a truncated cone, adapted to rest on the top of the receptacle B and having a flange or skirt 11 spaced inwardly from its outer edge 12, said skirt fitting snugly inside the receptacle. When the cover is placed on the receptacle, it extends outwardly beyond the walls thereof. A relatively large opening 13 is formed in the top of the cover 10.

A housing 14, supported above the cover 10 by straps 15, is formed with a removable cover 16 and a concave bottom 17 having an opening 18 centrally thereof. Fluid operated means, such as a water wheel 20, is fixedly mounted in the housing 14 upon a relatively large tube 21 which 25 extends downwardly through the opening 18 in the bottom of the housing, through the opening 13 in the cover 10 and below the latter. A packing gland 22 extends downwardly from the bottom 17 around the tube 21 and packing 23 is 30 held therein by a packing nut 24. A plurality of holes 25 are formed in the tube 21 between the hub of the water wheel and the bottom 17 of the housing 14. Fluid, such as water, air or 35 gas, is supplied to the housing 14 through a pipe 26 which communicates with the interior of the housing at a tangent thereto, the other end of 40 said pipe being connected to a suitable source of supply (not shown).

The tube 21 extends downwardly below the 45 cover 10 into the receptacle B and terminates adjacent the bottom thereof (see Fig. 4). Branch pipes 27 and 28 communicate with the tube 21 at its lower end. These branch pipes, extending outwardly from the tube 21 at substantially right 50 angles thereto, are each bent at 30 into a vertical position and again at 31 whence they extend back to the tube 21. At this point, the pipes 27 and 28 are again bent into a vertical position 55 and extend upwardly along the tube through the

cover 10, terminating above the latter. The opening 13 in the cover is large enough to permit the passage of the pipes 27 and 28 and the tube 21 without the latter pipes touching the cover. 5 A cone-shaped member 32 is mounted on the tube 21 spaced above the cover 10, said member overlapping a substantial portion of the cover. The ends of the branch pipes 27 and 28 opposite those communicating with the tube 21 open outwardly through the conical member 32 at 33 and 34, respectively. 10 A bearing rod 35, anchored in the cover 16 at 36 and suspended from the housing, extends downwardly into the tube 21 centrally thereof 15 and terminates in a ball bearing 37. A bearing plate 38 is mounted in the tube and is provided with a central orifice 40 through which the rod 35 freely extends. The plate 38 is adapted to rest upon the ball 37 so that the tube 21, branch 20 pipes 27 and 28, member 32 and water wheel 20 are all carried by said ball bearing.

In operation, a fluid, such as, for example, water, is supplied under pressure to the housing 14 through the pipe 26. The water causes the water 25 wheel 20 to rotate which, in turn, causes the tube 21 and the pipes 27 and 28 to rotate about the axis thereof. At the same time, the water is discharged from the housing 14 through the holes 25 into the tube 21, from which it flows into the 30 branch pipes 27 and 28. Finally, the water flows out of the branch pipes at 33 and 34 over the conical member 32 and passes over the cover 10. The tube 21 and the pipes 27 and 28 form an agitator extending downwardly from the housing 35 which is rotated by the wheel 20. As the agitator rotates, it stirs and rapidly cools the milk in the receptacle B. The hot air rising from the milk is free to pass through the opening 13 and out 40 through the space between the cover and the conical member 32. The whole agitator and its associated parts are supported entirely by the bearing 37 upon which the plate 38 rests. The only other point of friction is where the packing 23 touches the tube 21. The friction at this 45 point, however, is almost negligible as the packing is kept very loose since it does not matter if a little water leaks through the gland 22. The water, after having passed through the device, continues to assist in cooling the contents of the receptacle B as it flows over the cover 10 and 50 down along the sides of the receptacle.

The friction has been reduced to such a point in this device that it takes very little pressure to operate the agitator. Nevertheless, if desired, a 55 motor (not shown) may be connected to the tube 21 for rotating the agitator, particularly if it is desired to cool the milk in an exceedingly short time. Compressed air or gas might be used in place of water as the motive power and cooling means. Another variation is that a hot fluid 60 might be utilized in this device for heating a liquid in the receptacle B.

The structure of this device is extremely simple and there are only three pipes to wash after each operation. The cover 10 keeps dirt, oil or grease out of the liquid in the receptacle B during 65 operation while the holes 25 in the tube 21 control the flow of water therein and, consequently, the speed of rotation of the agitator.

From the above, it will readily be seen that a device for rapidly cooling milk or any other liquid has been provided which is very simple in construction, extremely effective and requires very little power for operation.

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set forth in the accompanying claims.

What I claim as my invention is:

1. A cooling device comprising a cover adapted to rest upon the top of a receptacle, a housing supported above the cover, an agitator extending from the housing freely through the cover and below the latter, said agitator including a vertical tube and at least one branch pipe communicating with the lower end thereof, a bearing suspended from the housing and extending a substantial distance into the vertical tube, said bearing being adapted to carry the agitator, and fluid operated means in the housing for causing the agitator to rotate.

2. A cooling device comprising a cover adapted to rest upon the top of a receptacle, a housing supported above the cover, an agitator extending from the housing freely through the cover and below the latter, a bearing suspended from the housing into the agitator, a bearing plate mounted in the agitator adapted to rest upon the bearing, said bearing being adapted to carry the agitator, and fluid operated means in the housing for causing the agitator to rotate about the bearing.

3. A cooling device comprising a cover adapted to rest upon the top of a receptacle, a housing supported above the cover, an agitator having a central tube extending from the housing freely through the cover and below the latter, a bearing rod extending downwardly from the housing into the agitator tube centrally thereof, a ball bearing on the lower end of the rod, a bearing plate mounted in the agitator tube having a central orifice through which the bearing rod freely extends, said plate being adapted to rest upon the ball bearing, and fluid operated means in the housing for causing the agitator to rotate about the ball bearing.

4. A cooling device comprising a cover in the form of a truncated cone adapted to rest upon the top of a receptacle, said cover having a relatively large opening in the top thereof, a housing supported above the cover, an agitator having a central tube extending from the housing freely through the opening in the cover and below the latter, a bearing rod extending downwardly from the housing into the agitator tube centrally thereof, a ball bearing on the lower end of the rod, a bearing plate mounted in the agitator tube having a central orifice through which the bearing rod freely extends, said plate being adapted to rest upon the ball bearing, and fluid operated means in the housing for causing the agitator to rotate about the ball bearing.

GORDON JOSEPH PEARDON.
